UNITED STATES PATENT OFFICE

2,325,888

GARMENT

Isidor Spencer, Chicago, Ill.

Application July 27, 1942, Serial No. 452,382

3 Claims. (Cl. 2—93)

The invention relates to garments such as coats and jackets, wherein the front, back and sleeves are made of a single piece of cloth, as described in my Patent No. 2,262,346 issued November 11, 1941.

It is an object of the present invention to provide a garment of the character described which presents a neat appearance and a perfect fit.

A further object constitutes the provision of a front yoke sewed with the bottom edge to the slitted edge of the body portion and with a side edge to the inner end of the tubular sleeve, the yoke being constructed also to provide a portion of the sleeve so as to assure a perfect fit for the garment.

Other and equally important objects will become apparent from a perusal of the invention which comprises the means disclosed in the specification, particularly pointed out in the claims forming a part thereof, and illustrated in the accompanying drawing in which:

Fig. 1 is a front view of a shirt made in accordance with my invention.

Fig. 2 is a developed view of the pattern used for making the improved shirt.

Fig. 3 is a plan view of the front yoke used with the shirt.

Fig. 4 is a fragmentary view showing the front yoke sewed to the shirt, and

Fig. 5 is a fragmentary view showing a further step.

In carrying out my invention, the front, back and sleeve portions of the coat are produced from a single piece of cloth, there being provisions made for the collar opening and proper shoulder fitting, when the sleeve portion integral with the coat proper is formed into a sleeve.

Referring to the drawing, 10 designates a single piece of cloth which has been cut and developed as shown in Fig. 2.

In commercial production the cloth is originally folded upon itself and cut to obtain the outline of the shirt. The bottom edge 11 determines the length of the shirt.

The upper end of the cloth is cut along an irregular line to provide a collar portion 12, triangular cut out portion 13 and inner end lines 14 of the sleeve portion 15. Each sleeve is provided with a triangular cut out portion 16.

A slit 17 at the junction of the sleeve and coat extends parallel to the bottom edge for a short length.

A front yoke 18 is employed which comprises a main portion 19 and an integral narrow extension 20.

The front yoke has a horizontal rectilinear edge 21, a short vertical edge 22, a concave edge 23 and a convex edge 24, leading to the extension 20.

5 In producing the shirt, the yoke 18 is sewn with the left end of its edge 21 (as viewed in Fig. 3) to the edge 25 of the shirt by a seam 26, as best shown in Fig. 4. Thereupon the extension 20 of the yoke is turned to the left, as viewed in Fig. 5, and the unsecured portion of the edge 21 is secured to the edge 27 formed by the slit 17. The sleeve portion 15 is arranged in tubular form and the edge 28 of the yoke is secured by a seam to an edge 29 of the sleeve portion. Finally, the lateral portion of the shirt is turned inwardly and the edge 24 of the yoke is sewed to the edge 15 of the sleeve portion.

The edge 23 of the yoke and the cut out portion 12 jointly form the neck opening.

It is evident that the yoke not only forms a part of the front portion of the shirt but also forms a part of the sleeve by reason of the yoke extension 20 extending the entire length of the sleeve.

25 While the drawing shows the invention applied to a shirt, it may also be applied to coats, pajama coats, sport coats, jackets, and similar articles of wearing apparel.

The precise dimensions, construction of parts 30 and their arrangement are only shown by way of example changes and alterations are included which constitute departures within the scope of the invention as defined in the appended claims.

35 I claim:

1. A coat comprising a body portion and sleeve portions made of a single piece of cloth, the juncture between the sleeve and body portion being slitted to permit tubular arrangement of the sleeves, and a front yoke sewed with the bottom edge to the slitted edge of the body portion and with a side edge to the inner end of the tubular sleeve, the top edge of the yoke complementing the neck opening and the other side edge forming a part of the front opening of the coat, the meeting edges of the sleeve and yoke being formed to afford shaping of the garment, the yoke being constructed to form a portion of the sleeve.

40 2. A coat comprising a body portion and sleeve portions made of a single piece of cloth, the juncture between the sleeve and body portion being slitted to permit tubular arrangement of the sleeves, and a front yoke sewed with the bottom edge to the slitted edge of the body portion

and with a side edge to the inner end of the tubular sleeve, the top edge of the yoke completing the neck opening and the other side edge forming a part of the front opening of the coat, the inner end of the sleeve having a concave edge and the side edge of the yoke being slightly convex resulting in shaping the garment, and means integral with said yoke for forming a portion of said sleeve.

3. A coat comprising a body portion and sleeve portions made of a single piece of cloth, the juncture between the sleeve and body portion being slit to permit tubular arrangement of

the sleeves, and a front yoke sewed with the bottom edge to the slit edge of the body portion and with a side edge to the inner end of the tubular sleeve, the top edge of the yoke complementing the neck opening and the other side edge forming a part of the front opening of the coat, the inner end of the sleeve having a concave edge and the side edge of the yoke being slightly convex resulting in shaping the garment, said yoke having an integral strip extension forming a portion of said sleeve throughout the length thereof.

ISIDOR SPENCER.
